UNITED STATES PATENT OFFICE.

SAMUEL E. DITTMAN, OF NEW YORK, N. Y., ASSIGNOR TO MIEELE PRINTING PRESS & MANUFACTURING COMPANY, OF CHICAGO, ILLINOIS, A CORPORATION OF ILLINOIS.

GRIPPER ATTACHMENT FOR PRINTING-PRESSES.

1,269,687.

Specification of Letters Patent. Patented June 18, 1918.

Application filed August 27, 1915. Serial No. 47,575.

To all whom it may concern:

Be it known that I, SAMUEL E. DITTMAN, a citizen of the United States, and a resident of New York, in the county of New York and State of New York, have invented certain new and useful Improvements in Gripper Attachments for Printing-Presses; and I do hereby declare that the following is a full, clear, and exact description thereof, reference being had to the accompanying drawings, and to the letters of reference marked thereon, which form a part of this specification.

This invention relates to improvements in gripper attachments for printing presses, and more in particular to an attachment adapted to be applied to the ends of the gripper fingers, which form a part of the paper or sheet retaining mechanism of a printing press.

To those skilled in the art of printing and familiar with the construction of printing presses and particularly that type known as the cylinder press, a common construction for such presses embraces, in general, a revolving cylinder provided with gripper fingers, acting to engage and hold the sheet to be printed during the printing operation, said cylinder being mounted in horizontal position upon the bed or frame of the press. The sheet of paper or material to be printed or receive the impression is applied to the revolving cylinder, which carries the paper, with a rotary motion, in contact with the type or printing form, the same being mounted upon the bed of the press, which travels forwardly and rearwardly beneath the cylinder with a reciprocating movement. To the surface of the cylinder or tympan is applied the blank sheet of paper, and upon receiving an impression, by its contact with the moving type forms, it is delivered or released from the cylinder and a blank sheet immediately applied and the printing operation again repeated.

Printing presses of this type are ordinarily provided with gripper fingers mounted upon or set in the cylinder and adapted to grip the front transverse margin of the sheets as the same are applied to the cylinder or, as commonly stated, "fed to the press."

A familiar construction for a gripper mechanism consists of a shaft set in the

cylinder adjacent to one margin of the tympan and extending transversely thereof, said shaft being provided at intervals throughout its length with a series of gripper fingers, which project at right angles to the shaft and are adapted to be moved into and out of contact with the surface of the cylinder by a rocking movement imparted to the shaft. When moved into contact with the cylinder, the gripper fingers grip the margin of a blank sheet of paper between their ends and the tympan, thus securely holding the sheet during the printing stroke, and release the sheet at the proper time. The gripper fingers are ordinarily made of metal and act to securely grip the sheet by pressure applied thereto through the medium of suitable tension means acting on the shaft.

Although it is the purpose, in the construction of the gripping mechanism, that all of the fingers shall exert an equal pressure upon the sheet whereby a uniform gripping action is present throughout the margin of the sheet, it has been found in practice that slight variations occur in the pressure exerted by the gripper fingers, due to various causes that will be hereinafter pointed out, and as a result the gripper fingers do not exert a uniform pressure throughout the margin of the sheet, and as a further result the sheets are not held firmly during the printing operation, thereby causing difficulty in obtaining proper registering of the sheet and type form and the maintaining of the proper margins on the sheets.

The purpose of my invention is to provide an attachment which may be easily applied to the ends of the gripper fingers, its purpose being to increase the gripping action of the fingers and to equalize the pressure thereof and thereby secure a uniform gripping of the sheet along its margin and eliminate the difficulties ordinarily encountered and as hereinafter more fully pointed out.

The features of my invention will now be described in detail, reference being had to the accompanying drawings, in which—

Figure 1 is a perspective view of a cylinder of a printing press, showing the arrangement of the gripper fingers;

Fig. 2 is a perspective view of one form of the gripper attachment;

Fig. 3 is a perspective view showing the contact surface of the gripper attachment shown in Fig. 2;

Fig. 4 is a perspective view of a modified form of the gripper attachment; and,

Fig. 5 is a sectional view of the modified form of the gripper attachment as applied to the end of a gripper finger.

Referring to the drawings, a clear understanding of the purpose of the gripper attachment may be had, and particularly with reference to Fig. 1, wherein is illustrated the cylinder 10 of a printing press provided with the before mentioned shaft 11 mounted upon the cylinder in a suitable manner and adapted to operate as before set forth. Mounted upon the shaft is a series of gripper fingers 12 extending transversely from said shaft in a downwardly direction and engaging a margin of a sheet of paper 13, which is held in printing position against the surface or tympan of the cylinder.

As already suggested, the gripper attachments are adapted to be applied to the ends 25 of the gripper fingers, and, although the same may partake of several forms, depending on the means employed in attaching them to the gripper fingers, all of the forms embrace a common member, namely, a pad 30 or block of material secured at the under side and at the ends of the gripper fingers and interposed between the ends of said fingers and the sheet of paper to be held. The pad or block is preferably composed of 35 rubber or other material of a soft, pliable nature and preferably having natural adhesive or gripping qualities.

Referring to one of the forms (Fig. 2), the same comprises a rectangular block or 40 pad 14 of rubber of a length preferably equal to the width of the gripper finger and a width sufficient to provide an ample gripping or contact surface. The block or pad is of sufficient thickness to space the fingers 45 from the sheet to be held thereby and to afford a suitable degree of resiliency. As shown, the thickness of the pad is slightly greater at the margin adjacent to the end of the finger than at its rear margin, there- 50 by affording the under or contact surface of the pad a slight taper from front to rear thereof with respect to the under surface of the finger. In this manner the contact surface of the pad assumes a more nearly tan- 55 gential position with respect to the surface of the cylinder, and as a result a better gripping contact is effected. The under or contact surface is, furthermore, serrated or roughened in any suitable manner, as shown 60 in Fig. 3, the obvious purpose of so doing being to increase the gripping tendency of the pad. In this form of the attachment the following means is employed to secure the same to the gripper fingers. Pro- 65 jecting upwardly from the upper surface

of the block 14 are provided two cylindric nubs or dowels 15 arranged symmetrically with respect to the longitudinal and transverse center lines of the pad and spaced apart from each other. These dowels are 70 preferably of rubber and molded integral with the block, the height of the same being slightly greater than the thickness of the metal fingers. These dowels are adapted to register with and to engage two apertures 75 similarly arranged at the end of each gripper finger. Thus, when the dowels are inserted in said apertures, the margins of the block and end portion of the gripper finger are substantially flush, said dowels projecting a short distance through the apertures, the diameters of the latter being substantially equal to that of said dowels to permit the block to be removably held in position. If desired, cement or glue may be 80 applied to the coacting surfaces of the parts, thereby affording a more permanent attachment.

In Figs. 4 and 5 is illustrated another form of the device, comprising a body member 16 preferably formed of rubber or like material molded into the desired form and open at one side and forming a pocket or space 17 therein, the dimensions of said pocket being substantially equal to the width 95 and thickness of the end portions of the gripper fingers. Extending from the opposite longitudinal edges of the pocket are two flaps 19, 19 of rubber. These flaps act as means for securing the attachment to the 100 gripper fingers, as will hereinafter appear. Upon one side of the body member and adjacent the pocket-forming portion thereof is the block or pad 20, of rubber or like material, rectangular in shape and integral with the body member, the same being formed, in effect, by materially increasing the thickness of one wall of the body member throughout one wall or side of the pocket. The surface of the pad 20 is roughened or serrated as 105 in the form of the attachment previously described. This form of gripper attachment is applied to the ends of the gripper fingers by inserting said ends thereof into the pocket formed by the body member, 110 with the pad 20 facing downward. As a means for securely holding the attachment in place, a pin 21 is preferably provided, which extends transversely through the gripper finger 12 (Fig. 5) and projects a 115 short distance above and below the surfaces of the finger. This pin is adapted to be engaged by apertures 22, 22 formed in the central portions of the flaps 19, 19; thus the attachment may be removably held in position by hooking the flaps to the pin, as 120 shown.

As has been before pointed out, the purpose of devices of this nature, and hence the advantage in their use, is to remove and 130

correct the difficulties that are encountered in the operation of the ordinary forms of gripping mechanisms. The chief difficulty has been suggested, namely, the inability to obtain a uniform gripping action or pressure along the margin of the sheet, due to marginal pressure throughout the entire series of gripper fingers exerted by the gripper fingers. This may be the result of one of several causes, such as a varying tension in the gripper fingers, a varying in the thickness of the paper stock used or in the thickness throughout all portions of a single sheet of paper, or a variation in the character of the surface of the paper stock being printed. The absence of a uniform gripping action during the printing operation often results in the sheet being shifted from its proper registering relation with the type form, and the consequent effecting of the improper location of the impression upon the sheet. Loss of time, labor, and material are manifestly the consequences. Furthermore, in case one or more of the gripper fingers exert an excessive pressure, it gives rise to a tendency by these fingers to dig, to an excessive degree, into the sheet and surface of the tympan with the attendant mutilation of the same. The presence of an elastic pad between the gripper finger and the sheets to be printed, however, tends to equalize the pressure exerted by the gripper fingers and to compensate for any excess pressure in one or more of the gripper fingers, by reason of the compressive and elastic features of the rubber pad or block, and to thereby eliminate the undesirable features of operation mentioned.

The equalizing and compensating effect of the gripper attachments together with

the natural gripping tendencies of the material itself makes it possible to secure the proper uniform operation of the press, regardless of the nature of the work or the length of time necessary to complete it, and to automatically correct any of the faults hereinbefore suggested that might arise during the operation of the press.

It is apparent from the foregoing description of the invention that such devices may be constructed in any one of several ways, and for that reason I do not wish to be limited to the particular construction herein shown and described, except in so far as specifically pointed out in the appended claims.

I claim as my invention:

1. The combination with a gripper finger of a printing press, of a pad member made of resilient material, and said pad member and said finger being provided with interengaging means adapted to removably connect said pad member with said finger and to hold said pad member from rotation with respect to said finger.

2. The combination with a gripper finger of a printing press, of a relatively flat pad member made of resilient material, and means for removably attaching said pad member to said finger, comprising a plurality of dowels integral with said pad member and extending into apertures in said finger.

In testimony that I claim the foregoing as my invention I affix my signature in the presence of two witnesses, this 23rd day of August, A. D. 1915.

SAMUEL E. DITTMAN.
